ATTORNEY.

UNITED STATES PATENT OFFICE.

ANDERS G. A. EKROTH, OF ISHPEMING, MICHIGAN.

BOTTLE-CLEANER.

SPECIFICATION forming part of Letters Patent No. 393,100, dated November 20, 1888.

Application filed May 10, 1888. Serial No. 273,441. (No model.)

To all whom it may concern:

Be it known that I, ANDERS GUSTAVE ANDERSON EKROTH, of Ishpeming, in the county of Marquette and State of Michigan, have invented a new and useful Improvement in Bottle-Cleaners, of which the following is a full, clear, and exact description.

My invention relates to an improvement in devices for cleaning bottles, and has for its object to provide a device of simple and durable construction, which may be readily inserted in a small vial or a large jug, and wherein the said device when rotated will not only clean the sides and bottom of the receptacle but also the ring-shaped cavity usually formed around and about the elevated portion of some bottles.

The invention consists in the construction and combination of the several parts, as will be hereinafter fully set forth, and pointed out in the claims.

Reference is to be had to the accompanying drawings, forming a part of this specification, in which similar figures of reference indicate corresponding parts in both the views.

Figure 1 is a side elevation of the device when expanded, and Fig. 2 is a side elevation of the same partially closed for insertion in the bottle to be cleaned.

The body of the invention consists of two vertical parallel side rods, 10, which rods are provided at the top and bottom and at the center with cross-bars 11, 12, and 13, respectively, the said cross-bars being pivoted to one face of the side rods. One of the rods 10 is made to project below the lower cross-bar, 12, and is provided with an attached tassel, 14, which tassel may be made of hair, hemp, or other suitable or equivalent material.

Upon the outer surfaces of the several side rods, and also the lower cross-bar, a series of bristles or hempen strands or equivalent brush-like material is attached, forming thereby side brushes, 15 and 16, and an end brush, 17, as best shown in Fig. 1. These brushes are preferably continuous, extending from end to end of their several supports.

A vertical rod, 18, is pivoted to the central cross-bar, 13, preferably slightly to the left of the center, which rod is carried upward beyond the upper cross-bar any suitable or desired distance. A second and parallel vertical rod, 19,

is secured preferably to the right of the center of the upper cross-bar, 11. The two rods 18 and 19 at their upper ends are pivotally secured to opposite sides of a horizontal hand-lever, 20, 55 at or near the center thereof. Below the hand-lever the said rods 18 and 19 are encircled by a collar, 21, in which they have freedom of motion, which collar is adapted, when the device is in use, to fit down and rest upon the neck of 60 the bottle or receptacle to be cleaned.

In operation, to clean a bottle, the hand-lever 20 is carried upward at one end, as shown in Fig. 2, which causes the rods 18 and 19 to act upon the respective cross-bars 11 and 13 65 and bring the same to an inclined or essentially vertical position, as desired. This movement of the cross-bars referred to causes the lower cross-bar, 12, to assume an equivalent position and likewise causes the side rods to approach 70 closely together. If the bottle is very small, the side rods may be made to almost touch, whereas if the orifice of the bottle is large they will be left wider apart. When the device has been inserted in the bottle, the hand-lever is 75 brought down again as near a horizontal position as possible, whereby the side brushes are brought in contact with the sides of the vessel, and the device having been pushed as far down as possible in said vessel the lower brush is 80 brought in contact with the bottom, while the tassel 14 is left to trail along the side in the crevice formed by the union of the vessel's sides and bottom. To complete the operation 85 of washing after the water and soap or other desired material has been inserted, the device being stayed or held in the receptacle by contact of the collar 21 with the mouth thereof, the said device may be rapidly revolved by means of the lever 20, and the receptacle thoroughly cleansed.

This simple, inexpensive, and durable device will more readily and thoroughly cleanse a receptacle, whether it be large or small, than the small leaden bullets, shot, or sand that has 95 heretofore been employed for this purpose.

Having thus fully described my invention, what I claim as new, and desire to secure by Letters Patent, is—

1. In a device for cleaning bottles and similar receptacles, the combination, with brush-carrying parallel side rods, a lower pivoted

brush-carrying cross-bar, and a central and an upper cross-bar, of a vertical rod pivoted at one side of the center of the central bar, a similar rod pivoted to the opposite side of the center of the upper cross-bar, and a handle pivotally attached to said rods, substantially as and for the purpose specified.

2. The combination, with parallel vertical brush-carrying side rods, a lower brush-carrying cross-bar pivoted to said rods, and a central and upper cross-bar also pivoted to the rods, of a vertical rod pivoted at one side of the center of the central bar, a similar rod pivoted to the opposite side of the center of the upper cross-bar, a horizontal handle pivotally united to said rods, and a tassel adapted to and pendent from the lower extremity of one of the side rods, substantially as and for the purpose specified.

3. The combination, with brush-carrying side rods, a lower brush-carrying cross-bar pivoted to said rods, a central and upper cross-bar also pivoted to the side rods, of a vertical rod pivoted to the left of the center of the central cross-bar, a similar rod pivoted to the right of the center of the upper cross-bar, a handle pivotally attached to the upper extremities of said rods, a collar revolving upon the rods between the upper cross-bar and the handle, and a tassel attached to and pendent from one of the side bars, substantially as and for the purpose specified.

ANDERS G. A. EKROTH.
